(57) **CLAIM**

The ornamental design for a programming device assembly for an implantable medical device, as shown and described.

DESCRIPTION

FIG. 1 is a perspective view of a programming device assembly for an implantable medical device, showing our new design;

FIG. 2 is a front view thereof;

FIG. 3 is a left side view thereof;

FIG. 4 is a bottom view thereof;

FIG. 5 is a right side view thereof;

FIG. 6 is a top view thereof; and,

FIG. 7 is a rear view thereof.

The broken lines in the drawing illustrate portions of the programming device assembly for an implantable medical device that form no part of the claimed design.

The oblique lines in the drawings indicate transparency.
